UNITED STATES PATENT OFFICE.

DANIEL F. MORGAN, OF TOLEDO, OHIO.

GLOVE.

SPECIFICATION forming part of Letters Patent No. 760,547, dated May 24, 1904.

Application filed February 1, 1904. Serial No. 191,496. (No model.)

To all whom it may concern:

Be it known that I, DANIEL F. MORGAN, a citizen of the United States, residing at Toledo, in the county of Lucas and State of Ohio, have invented certain new and useful Improvements in Gauntlets or Gloves, of which the following is a specification.

This invention relates to improvements in gloves, and has especial relation to that class thereof having long wrist extensions or cuffs and known as "gauntlets;" and it consists in certain peculiarities of the construction, novel arrangement, and operation of the various parts thereof, as will be hereinafter more fully set forth, and specifically claimed.

The principal object of the invention is to provide a gauntlet or glove which is especially designed for the use of chauffeurs, motormen, engineers, firemen, bridge-builders, linemen, and others who require a durable and well-fitting gauntlet or glove which shall be so made as to prevent the admission of dust, cold air, or wind up the garment-sleeve of the wearer, as well as to permit of the free and unrestrained movement of the hand at the wrist in any direction.

Another object is to provide a gauntlet of the above-named character which shall be of such construction that it can be easily put on or readily and quickly withdrawn or pulled off the hand in a case of emergency, which often occurs with chauffeurs and railroad men.

Still another object is to so connect the cuff portion with the body of the glove or hand-covering that they will virtually have independent movement of one another—that is to say, the cuff portion when in position on the arm and coat-sleeve will remain practically in a stationary position, thus preventing it wearing the nap of the coat-sleeve, while the hand with the glove portion thereon may be turned in any direction.

Other objects and advantages of the invention will be disclosed in the subjoined description and explanation.

In order to enable others skilled in the art to which my invention pertains to make and use the same, I will now proceed to describe

it, referring to the accompanying drawings, 50 in which—

Figure 1 is a top plan view of a gauntlet embodying one form of my invention. Fig. 2 is a view in elevation of the palm side of the gauntlet, showing the thumb-piece turned 55 downwardly. Fig. 3 is an enlarged bottom plan view of the cuff portion and a part of the glove or hand-covering. Fig. 4 is a detail view of the gore used in connecting the lower portions of the pieces comprising the 60 cuff portion of the gauntlet. Fig. 5 is an enlarged sectional view taken on line 5 5 of Fig. 2 looking in the direction indicated by the arrows and showing the glove portion turned laterally with respect to a portion of a cuff 65 and illustrating the position assumed by a portion of the connection between said parts. Fig. 6 is a detached view of one of the connecting-pieces used for uniting the glove or hand-covering to the inner portion of the cuff 70 of the gauntlet; and Fig. 7 is a view in side elevation of the palm side of a portion of the gauntlet, showing a modification in the construction thereof.

Like numerals of reference refer to corresponding parts throughout the different views of the drawings.

The reference-numeral 10 represents the body of the glove or hand-covering, which may be of the ordinary or any preferred construction and made of any suitable material.

That portion of the glove or hand-covering which when in position on the hand lies about the wrist ends in parallel edges 11, having an inwardly-extending "V-shaped" recess 12, in 85 which is secured, by means of stitches or otherwise, the inner end of the gore 13, which is employed to unite the lower edges of the parts 14 and 15, which, together with the gore and connecting-pieces 16, form the cuff portion 90 17 of the gauntlet.

As will be readily understood by reference to Fig. 2 of the drawings, the cuff portion 17 is mainly made up of two pieces 14 and 15, which are counterparts of one another and 95 preferably of the shape shown in said figure—that is, each of said sections consists of a piece tapered from its outer end to its inner por-

tion and formed at its inner portion with an outwardly-curved recess 18, to the edges of each of which are secured, by means of stitches or otherwise, the curved edges of each of the connecting-pieces 16, which have their other edges straight and parallel with one another and are attached to the edges 11 of the wrist portion of the glove or hand-covering.

The portions forming the cuff 17 and connecting-pieces 16 may be of any suitable material; but I usually make the connecting-pieces 16 out of the same kind of material that the glove 10 is formed of and make the portions comprising the cuff of somewhat 15 heavier, stiffer, and thicker material, so that it will normally present a cuff portion in cross-section approximately in the form of a narrow vertical oval, slightly tapered toward its inner portion and adapted to expand when it 20 is slipped over the wearer's sleeve and, through its natural resiliency, to embrace said sleeve and maintain a proper set of the gauntlet thereon. The connecting portions 16, uniting the inner portions of the cuff 17 to the wrist portion of the glove, are quite flexible and, as will be clearly understood by reference to Fig. 3, when in place present an outwardly-flaring or enlarged portion around the wrist of the wearer, thus allowing the gauntlet to be easily 25 put on or quickly and readily removed without the least restraint. This flexible connection will when the hand is bent laterally in either direction permit free movement of the hand and glove thereon without disturbing 30 the position of the cuff to any material extent and when bent laterally will pucker or form into smaller bends, as is clearly shown in Fig. 5 of the drawings. To permit of the vertical movement of the hand without restraint, the 35 seam 19, which unites the thumb-piece 20 to the back of the glove, is extended forwardly of the upper longitudinal meeting edges 21 of the sections 14 and 15, forming a part of the cuff, or is extended toward the palm portion 40 of the glove, as is clearly shown in Figs. 1, 2, and 7 of the drawings.

The gore 13, which unites the sections 14 and 15, comprising the cuff at their lower longitudinal edges 22, is preferably made of material possessing more flexibility than that of the said sections, and as the gore extends into the recess 12 of the wrist portion of the glove it is apparent there will be little or no resistance against the downward movement of the hand.

In Fig. 7 of the drawings I have shown a modification in the construction of the gauntlet which consists in forming the inner ends of the sections 14 and 15, comprising a part 55 of the cuff, with curved recesses 18, as in the first-named construction, to receive the curved edges of the connecting portions 23 on the front and rear of the wrist portion of the

glove, which in this modified construction are made integral therewith instead of being sewed 65 to the edges 11, as in the first-named construction; otherwise this modified form of the gauntlet does not differ from that shown in Figs. 1 to 6, inclusive, and above described.

From the foregoing and by reference to the 70 drawings it will be readily seen and clearly understood that by my construction I afford a gauntlet which may be readily placed on the hand and quickly removed therefrom and which has no elastic or drawn portions to bind 75 or encumber the wrist of the wearer. It is also evident that the coat-sleeve of the person wearing the glove will not be worn by the continuous movement of the cuff, as by my construction the cuff is held practically motionless on the sleeve and in such a manner as to permit of the utmost freedom of the hand in any direction.

Having thus fully described my invention, what I claim as new, and desire to secure by 85 Letters Patent, is—

1. In a gauntlet, the combination with a hand-covering having the seam which secures the rear portion of the thumb-piece thereto extending toward the palm side, of a cuff portion comprising two pieces, each having a curved recess at its inner end, and a gore connected to the lower longitudinal edges of said pieces and at its inner end to the wrist part of said covering, the upper longitudinal edges of 95 said pieces being connected together and to the hand-covering at the rear of said thumb-piece-securing seam, and connecting portions having curved parts connected to the curved edges of the cuff portion, and united to the 100 wrist part of the hand-covering, substantially as described.

2. In a gauntlet, the combination with a hand-covering made of flexible material and having the seam which secures the rear portion of the thumb-piece thereto extending toward the palm side and provided in the lower part of the wrist portion with a recess, of a cuff portion comprising two pieces of less flexible material than the hand-covering, means 110 uniting the inner end of the cuff portion with the wrist portion of the hand-covering, a gore of material more flexible than the cuff-portion pieces connected to the lower longitudinal edges of said cuff-portion pieces and at its inner end to the edges of the recess in the wrist part of the hand-covering, the upper longitudinal edges of said cuff-portion pieces being connected together and to the hand-covering at the rear of said thumb-piece-securing seams, 115 substantially as described.

DANIEL F. MORGAN.
